UNITED STATES PATENT OFFICE.

ALLEN A. BOWSER, OF FORT WAYNE, INDIANA.

ADJUSTABLE STOP DEVICE.

1,137,454.

Specification of Letters Patent. Patented Apr. 27, 1915.

Application filed July 9, 1913. Serial No. 777,396.

To all whom it may concern:

Be it known that I, ALLEN A. BOWSER, a citizen of the United States, residing at Fort Wayne, in the county of Allen and State of Indiana, have invented certain new and useful Improvements in Adjustable Stop Devices, of which the following is a specification.

My invention relates to adjustable stop devices and has for its primary object the provision of an improved device of this character.

With the above and other objects in view, this invention consists substantially in the combination, construction, and arrangement of parts all as hereinafter described, illustrated in the accompanying drawings which form a part of this specification and show the preferred embodiment of my invention, and more particularly set forth in the subjoined claims.

In the drawings: Figure 1 is an elevation of a pump embodying my invention. Fig. 2 is a section taken on the line 2—2 of Fig. 1 and looking in the direction indicated by the arrows. Fig. 3 is an enlarged view of a portion of the section shown in Fig. 2 and illustrating a different position of the parts. Fig. 4 is a section taken on the line 4—4 of Fig. 3 and looking in the direction indicated by the arrows. Fig. 5 is a view in perspective of the lower end of a rack shown in Figs. 1, 2, and 3.

Reference numeral 10 indicates a toothed rack used in actuating a pump designated A, the rack receiving its power from the pinion 11 with which it is in mesh, a driving shaft 12 upon which the pinion 11 is secured, and a handled crank 13. The reciprocal motion of the rack 10 actuates the pump. Upon the bottom of the rack is formed a foot 14 having an inwardly and downwardly cut binding surface 15. A threaded rod 16 is secured to the pump in a position parallel and adjacent to both the rack 10 and the barrel of the pump. Upon the threaded rod 16 are disposed any desired number of adjustable pivoted stops, each of which in a certain position may be made to coöperate with the foot 14 to limit at any desired point the upward travel of the rack 10 and thereby limit the discharge of the pump A. In Fig. 2 is illustrated a top plan view of one of these pivoted adjustable stops. The stop comprises an inwardly threaded sleeve 17 provided with

out-turned flanges 18 on its ends, the flanges being pierced or slotted about their peripheries as at 19. A segmental detent in the form of a semi-circular piece of metal 20 fits closely against the outer surface of the sleeve 17 and fills the space between the flanges of the sleeve, while a clamping yoke 21 secured to the detent by any convenient means such as the cap screws 22 fits upon the opposite side of the sleeve 17 in a manner similar to the way in which the detent 20 fits. The distance from the center of the threaded rod 16 to the outer ends of the clamping yoke 21 and to the outer periphery of the segmental detent 20 is greater than the distance from the center of the rod 16 to the barrel of the pump A, while the distance from the center of the threaded rod 16 to the central point of the outer surface of the clamping yoke 21 is less than the distance from the center of the rod to the barrel of the pump. The sleeve 17 may be caused to travel upon the threaded rod 16 in either direction by rotation about the rod 16 and as it travels upon the rod it will carry along the segmental detent 20 and the clamping yoke 21. If it is desired to operate the stop from a given position on the rod, the sleeve 17 is rotated upon the rod until the stop is at the proper place, whereupon a seal 27 is passed through apertures provided in the detent 20 and the yoke 21 as well as through those slots of the flanges 18 which register with the apertures provided. In this manner rotation of the sleeve 17 upon the threaded rod is limited to that part of a complete rotation allowed by the formation of the detent and yoke which, as is seen in the drawings, is preferably a half revolution or less. The whole stop is free to move pivotally upon the rod 16 but cannot be made to travel along it continuously while the seal is in place.

In Figs. 1 and 2 is shown the inoperative position of the stop, while in Fig. 3 the stop is illustrated as thrown into operative position, that is, into a position where it will coöperate with the binding surface 15 upon the foot 14 to limit the stroke of the pump. When the stop is in the position shown in Figs. 1 and 2, the foot 14 is unobstructed by it and may pass it freely. When, however, the stop is in the position shown in Fig. 3 the segmental detent 20, which is inwardly and upwardly cut upon its under side to provide a binding surface 23 for co-

operation with the binding surface 15, lies in the path of the foot 14 and contacts with the foot to limit the stroke of the pump.

One feature of my invention is the positions occupied by the binding surfaces 15 and 23 with relation to each other, these surfaces being so disposed that though great upward pressure be exerted upon the rack it cannot be made to bend or slip away from the stop, but will be held against lateral movement with respect thereto. A spring 24 secured to the stop at one end contacts with its free end against the barrel of the pump A and serves to retain the stop against casual dislodgment from either of its pivotally adjusted positions. For convenience in manipulation a handle 25 protrudes preferably from the segmental detent 20, and for further convenience a plate 26 is positioned upon the outer periphery of the stop and bears any suitable legend such as "One gallon".

In the operation of the pump the turning of the handled crank 13 causes upward movement of the rack 10 and the foot 14. That stop which designates the amount of fluid which it is desired to discharge from the pump is thrown into the position illustrated in Fig. 3 and when the foot 14 has risen to that stop the two binding surfaces 15 and 23 contact and prevent the discharge from the pump of more than the desired quantity. If it be found that the quantity discharged by the pump when the stop 14 and the detent have met is incorrect, the seal 27 is removed, the sleeve 17 rotated upon the threaded rod 16 until the proper point is reached, and the seal again set in place.

In the accompanying drawings and in the foregoing description is set forth the preferred embodiment of my invention, but it is obvious that one skilled in the art may make modifications thereof without departing from the spirit of the invention.

45 I claim:

1. The combination of a threaded rod, a sleeve threaded upon the rod and having peripheral flanges at its ends, a stop projecting laterally of the rod and fitted for rotation about the sleeve and between the flanges thereof, and means for securing the sleeve and stop in fixed relation.

2. The combination of a threaded rod, a movable sleeve threaded upon the rod, and having peripheral flanges at its ends, and a stop projecting laterally of the rod, disposed about the sleeve and fitted rotatable between the flanges thereof.

3. The combination of a threaded rod, a movable sleeve threaded upon the rod, and having peripheral flanges at its ends, and a stop projecting laterally of the rod, disposed about the sleeve and fitted between the flanges thereof, said stop being formed of two pieces removably secured together.

4. The combination of a threaded rod, a removable sleeve threaded upon the rod and having peripheral flanges at its ends, a wall parallel and adjacent to the rod, a segmental stop of greater width than the distance between the rod and the wall, disposed about part of the sleeve and fitted between the flanges thereof, and a yoke secured to the ends of the segmental stop disposed about the remainder of the sleeve and fitted between the flanges thereof, said yoke being at its center of lesser width than the distance from the rod to the wall. 70

5. The combination of a threaded rod, a movable sleeve threaded upon the rod and having peripheral flanges at its ends, a wall parallel and adjacent to the rod, a segmental stop of greater width than the distance between the rod and the wall, disposed about part of the sleeve and fitted between the flanges thereof, a yoke secured to the ends of the segmental stop disposed about the remainder of the sleeve and fitted between the flanges thereof, said yoke being at its center of lesser width than the distance from the rod to the wall, and means for securing the stop and sleeve in fixed relation. 80

6. The combination of a threaded rod, a movable sleeve threaded upon the rod and having peripheral flanges at its ends, a wall parallel and adjacent to the rod, a segmental stop of greater width than the distance between the rod and the wall, disposed about part of the sleeve and fitted between the flanges thereof, a yoke secured to the ends of the segmental stop, disposed about the remainder of the sleeve and fitted between the flanges thereof, said yoke being at its center of lesser width than the distance from the rod to the wall, and a seal passing through the stop, yoke, and sleeve and securing the stop and yoke in fixed relation to the sleeve. 90

7. The combination of a threaded rod, an adjustable pivoted stop thereon, a wall adjacent and parallel to the rod, and a spring member in contact with the stop and wall and for movably maintaining the stop in position at either end of its path of pivotal movement.

8. The combination of a rod, a stop pivoted upon the rod and adjustable longitudinally thereof, a wall parallel and adjacent to the rod and with which the stop contacts at each end of its path of pivotal movement, and means co-operating with the wall and stop to maintain the stop movable in position at either end of its path of pivotal movement. 115

9. The combination of a threaded rod, a sleeve threaded upon the rod and having peripheral flanges spaced apart, a segmental stop secured about the sleeve and fitted between the flanges thereof, said sleeve being movable upon the rod, a wall adjacent the rod, means for securing the sleeve and stop 125

in fixed relation, said segmental stop being
of sufficient width to contact with the wall
at each of its ends, and a spring member
carried by the stop and contacting with the
wall for removably maintaining the stop in
position when either of its ends is in contact
with the wall.

In testimony whereof I have signed my

name to this specification, in the presence of
two subscribing witnesses, on this 3rd day of 10
July A. D. 1913.

ALLEN A. BOWSER.
